UNITED STATES PATENT OFFICE.

HENRI R. HENDERSON, OF ST. LOUIS, MISSOURI.

WALL-CLEANING COMPOUND.

No. 839,290.

Specification of Letters Patent.

Patented Dec. 25, 1906.

Application filed January 13, 1906. Serial No. 295,867.

To all whom it may concern:

Be it known that I, HENRI R. HENDERSON, a citizen of the United States, residing in the city of St. Louis, in the State of Missouri, have invented certain new and useful Improvements in Wall-Cleaning Compounds, of which the following is a full, clear, and exact description.

My invention relates to an improvement in compounds for use in what is termed the "dry-cleaning process" of cleaning the walls and ceilings of buildings, and particularly the decorations thereon, such as wall-paper.

The invention has for its object to produce a compound of the character named that is not liable to become deteriorated and which is preservable in condition for use for any reasonable period and may be utilized without preparation on the part of the user.

Briefly stated, the compound consists of a paste produced by combining flour or other starchy material, water, sodium chlorid, alum, carbolic acid, sodium bicarbonate, and common chalk. While the proportions in which the ingredients of my compound may be varied more or less, and I therefore do not wish to be restricted to any exact proportions, I prefer the following: fifty-two parts of flour, nine parts of sodium chlorid, thirty-seven parts of water, one part of carbolic acid, two-tenths of one part of alum, six-tenths of one part of sodium bicarbonate, and two-tenths of one part of common chalk.

In preparing my compound I first mix together all of the ingredients to cause all of them to become thoroughly commingled in a mass of the consistency of paste. I then subject said mass to the action of heat for a sufficient length of time to cook it and cause the water therein to be thoroughly absorbed by the various ingredients, whereby the mass, which was previously of paste-like consistency, is transformed into a cooked and kneadable dough, which may be readily worked in the hands, but which is slightly disintegrable under frictional action, in order that when the material is to be used in cleaning a surface, such as a wall, it will break into small rolls as the dirt is gathered thereon.

I wish to here call attention to two of the ingredients that enter into my compound, and in the use of which in combination with the other ingredients of a wall-cleaning compound my present improvement resides.

These ingredients are the sodium bicarbonate

and common chalk. The sodium bicarbonate is used for the purpose of preventing and removing the characteristic stickiness that is commonly present in wall-cleaning compounds and also to prevent the compound from becoming sticky from age or exposure to heat, and more particularly to heat to which the compound is subjected by its being absorbed from the natural heat of the hands of a person using the compound and friction of the compound on a wall during a cleaning operation. A compound prepared without including sodium bicarbonate therein will become so sticky as to render it extremely unsatisfactory in use, due to its sticking to the surface being cleaned whenever the compound is permitted to rest against the surface without being moved thereon, as at the end of each cleaning stroke. This sticking of the compound to the surface causes marks of dirt to be left on the surface which cannot be eradicated. The presence of the sodium bicarbonate in the compound removes the objectionable stickiness and obviates the formation of dirt-marks on the cleaned surface. Moreover, the compound if prepared without the addition of the sodium bicarbonate will become too soft and sticky for satisfactory use when exposed to a warm temperature or from age.

The common chalk is used in the compound for the purpose of rendering it more readily disintegrable in order that the compound will break into minute rolls when rubbed over the surface of a wall and whereby the dirt upon such surfaces is more readily removed, due to the better disintegration of the mass.

I claim as my invention

1. In a compound of the character described, the combination of flour, sodium chlorid, water, carbolic acid, alum, sodium bicarbonate and common chalk.

2. A compound of the character described consisting of fifty-two parts of flour, nine parts of sodium chlorid, thirty-seven parts of water, one part of carbolic acid, two-tenths of one part of alum, six-tenths of one part of sodium bicarbonate, two-tenths of one part of common chalk.

HENRI R. HENDERSON.

In presence of—

E. S. KNIGHT,
NELLIE V. ALEXANDER.
